PUSH BUTTON CONSTRUCTION

Herbert Young, Grand Rapids, Mich., assignor to
 National Brass Company, Grand Rapids, Mich.,
 a corporation of Michigan

Application February 27, 1950, Serial No. 146,546

8 Claims. (Cl. 292—336.3)

1

The present invention relates to novel, practical and economical improvements in the push button control associated with the knob for the inner side of a door, in the application for patent, filed September 2, 1948, having Serial No. 47,438 by Herbert Quigley.

Such push button structure, installed axially in the knob is utilized to open the door from its inner side whether or not the door may be locked against being opened at its outer side, except with a key for such purpose. This push button structure is operatively joined to the locking mechanism for the outer knob by an elongated flat bar extending through the door. This flat bar is moved in the direction of its length, when the push button on the inner knob is pushed in and is rotated or oscillated with the turning of said push button. This bar, in the Quigley application previously identified, through its operation, removes the barrier associated with the outside knob which barrier prevents the outside knob from retracting the latch or lock bolt.

It is an object and purpose of the present invention to produce a novel, more practical and economical structure, designed to secure like results in a better and more facile manner, with economy of structure. The invention also permits the use of one length only of the flat bar associated with the push button for different thicknesses of the door on which the mechanism of the Quigley previously identified application is installed. The push button, in the operative association with such bar engages the bar inwardly of the notched weakened portions of the bar. At these notches predetermined short lengths of the bar may be broken away in utilizing such bar for a lesser thickness of door. No breaking removal of end portions of the bar is made for the greatest thickness of door with which the structure is used, and progressively longer parts are broken from such bar as the thickness of the door, on which the latch is installed, is progressively reduced.

An understanding of the invention may be had from the following description taken in connection with the accompanying drawings, in which,

Fig. 1 is a partial side elevation and vertical section through the novel push button structure, the plane of the section being substantially that indicated on line 1—1 of Fig. 2.

Fig. 2 is a transverse vertical section through the push button, substantially on the plane of line 2—2 of Fig. 1, and

Fig. 3 is a horizontal section through the push

button structure substantially on the plane of line 3—3 of Fig. 2.

Like reference characters refer to like parts in the different figures of the drawings, and the sections are taken in the directions indicated by the arrows associated with the section lines.

In the environment where the present invention is used, a knob body 1, which may be of sheet metal reinforced at its inner side, is open at its end nearest a door on which it will be installed. This open end is closed by a closure portion 2 snapped into place. The knob has a generally cylindrical knob shank 3 of thin metal flanged at its outer end and connected by screws to an adapter 4. The adapter 4 is welded or otherwise permanently connected at the inner side of the outer end of the knob body 1. The knob shank 3 extends beyond the inner side of the knob through a sleeve 5 of an escutcheon or rose 6 which, in practice, is permanently secured at the inner side of the door.

The push button 7, with which this invention is concerned, is axially located in the outer portion of the knob body. It has a projection 8 flattened at both ends at its outer end. The knob may be moved bodily inwardly lengthwise of the knob shank 3 into which it telescopes or may be turned about its longitudinal axis by manual engagement of the projection 8. The push button 7 is normally moved outwardly by a coiled compression spring 9 of relatively light strength. A flat bar 10 of thin metal is located axially of the knob shank 3, its outer end portion extending to the bottom of an inner chamber shown in the button 7. The bar 10 extends through the door and to the knob assembly at the outer side of the door, as shown and described in the previously identified Quigley application.

In this environment, my invention is applicable, as is about to be described. The chamber within the button 7 is axially located, of a relatively long length and closed at its bottom by the outer end of the button 7. The bar 10 is axially located in this chamber. At its end within the chamber its edges are notched at directly opposite points, as indicated at 11. One series of notches 11 only is shown, but between such notches and the other end of the bar similar pairs of notches spaced from each other may be made. Within the chamber a yielding or spring holding and engaging means for the bar 10 is located. It is of flat spring bar stock, having an intermediate section 12 seated against the bottom of the chamber in the button 7, from the

55

ends of which parallel legs 13 extend toward the opening of the button. The legs are reversely bent upon themselves in U-turns extending toward each other, and terminate in end portions 14 parallel to the legs 13. The end portions 14 press with a yielding or spring force against opposite sides of the bar 10.

Inwardly of this bar holding member, a cup member of sheet metal is assembled and installed in the button 7. The cup member has a bottom 15 bowed outwardly in concavo-convex form with a rectangular slot 16 at its central portion through which the bar 10 loosely passes. The walls 17 of the cup member engage with the adjacent walls of the chamber in the button 7 and, either by press fit or the equivalent thereof, such cup member is fixed to the push button 7 and moves therewith. At the outer free edges of the walls 17, triangular tongues 18, spaced from each other, are bent toward each other and are located to hold the legs 13 of the previously described bar holding member in position. Such holding engagement requires the bar engaging member described to turn when the push button is rotated. In assembly, the annular lip shown at the inner end of the button 7 is spun or otherwise turned inwardly to hold the assembled parts in place against disconnection.

With this construction, the bar 10 may be moved axially against the spring 9 of the knob shank when the push button 7 is pressed. Such bar 10 also turns or oscillates upon like operations of the push button. The bar 10 is also securely held in its axial location and does not shift therefrom. It will be noted that the bar 10 is turned by the bottom 15 of the cup member when the edges of the rectangular opening 16 therein bear against the bar, and that the force applied to the bar for such turning is inwardly beyond the innermost notches 11. This is true irrespective of whether or not the bar 10 is shortened by breaking off portions at any selected pair of notches 11. The turning force applied to the bar 10 is not transmitted through any weakened portion of the bar at such notches, insuring against the bar breaking in service at the notched and weakened portions.

The structure described is useful and practical and is one which has been adopted in manufacturing the structures, like that shown in the above identified Quigley application or those which work upon identical principles having substantially identical structure.

The invention is defined in the appended claims and is to be considered comprehensive of all forms of structure coming within their scope.

I claim:

1. A knob, a shank centrally thereof having a longitudinal opening therethrough, a longitudinally movable and rotatable push button centrally of said knob at the outer portion thereof and extending into said shank, said push button having a chamber from its inner end outwardly, closed at its outer end, a flat bar lengthwise of said knob shank extending into said chamber, a member within said chamber at the inner portion of the push button having a passage through which the bar passes secured to said push button, a locating element within the chamber yieldingly engaging said bar at opposite sides, means for operatively connecting said member with said locating element to cause them to move in unison with the push button.

2. In a structure as described, a generally cylindrical knob shank, a knob secured thereto

at the outer portion of the shank, a push button slidably and rotatably mounted on said knob and shank, the push button extending into the shank, said push button having an axial chamber open at its inner end and closed at its outer end, a spring in the knob shank normally moving the push button outwardly, a flat bar located lengthwise and axially in the knob shank, having its outer end portion extending into said chamber, a cup member secured in the inner portion of said chamber to the push button, having a bottom with a slot therein through which the bar passes, said cup member at the outer edges of the sides thereof having inwardly extending projections, and a locating and holding member of generally U-shape, having a pair of inwardly extending legs and an intermediate portion, said intermediate portion bearing against the closed end of said chamber and against which the outer end of said bar engages, and inwardly extending sides, the terminal portions of which bear against said bar at opposite sides thereof, said legs extending between spaced projections of said cup member, said opening in the bottom of the cup member through which the bar passes being of a form complementary to the cross-section of the bar, whereby the bar is turned about its longitudinal axis on rotation of said push button.

3. A structure as defined in claim 2, wherein said projections on said cup member are disposed in pairs and said locating and holding member is formed of an elongated bar of flat metal, the inwardly extending legs of which lie between the projections of opposite pairs of projections, and being return bent to provide terminal portions yieldingly pressing against opposite sides of said bar.

4. In a structure as described, a cylindrical shank, a knob secured to the shank, a push button rotatably and longitudinally mounted on said knob and extending into shank, said push button having a chamber extending from its inner end outwardly for a distance, a bar extending into said chamber, a member secured to said push button within said chamber through which the bar passes for turning the bar upon rotation of the push button, and a yielding spring member located within the chamber having opposite yielding terminal portions normally moving toward each other and bearing against opposite sides of the bar.

5. A structure as defined in claim 4, wherein means are provided on said member through the bottom of which said bar passes for operatively engaging said spring member at both sides of the bar to connect said spring member therewith and to cause its turning with the push button.

6. A structure as defined in claim 2 wherein said projections of said cup member are disposed in pairs and said locating and holding member is formed of an elongated bar of flat metal, the inwardly extending legs of which lie between the projections of opposite pairs of projections, said inwardly extending legs being reverse bent to provide terminal portions yieldingly pressing against opposite sides of said bar, said bar at its outer end portion, beyond the bottom of said member through which it passes, being transversely weakened by removal of material in said bar whereby the bar may be broken at such weakened portion.

7. In a structure as described, a rotatable knob, a push button mounted on said knob for longitudinal movement, said button being hollow and having an entrance opening at its inner end, a

rod having an end inserted into said button through said opening, and spring gripping means within said button engaging said rod, the inner end of said button being of sheet metal formed separately from the body thereof for retaining said spring gripping means within said button.

8. In door handle construction, the combination comprising: a knob; a tubular shank mounted to said knob centrally thereof; a push button mounted centrally in the outer portion of said knob and extending into said tubular shank, said push button being adapted for rotation and movement axially of said shank; said push button having therein a chamber open at its inner end and closed at its outer end; a flat bar extending through said shank and having one end received into said chamber; a member within the inner end of said chamber and secured to said push button and having a passage therethrough

10

5

through which passes said bar; a locating element within said chamber yieldingly engaging said bar on opposite sides thereof; projections on said member for operatively connecting said member with said locating element to cause said locating element to rotate in unison with said push button.
